UNITED STATES PATENT OFFICE.

JOSEPH E. LEONARD, OF CEDAR RAPIDS, IOWA.

TENT-STOVE.

1,352,290.

Specification of Letters Patent.

Patented Sept. 7, 1920.

Application filed February 25, 1919. Serial No. 279,131.

To all whom it may concern:

Be it known that I, JOSEPH E. LEONARD, a citizen of the United States, residing at Cedar Rapids, in the county of Linn and 5 State of Iowa, have invented certain new and useful Improvements in Tent-Stoves, of which the following is a specification.

My invention relates to new and useful improvements in tent stoves.

10 The object of the invention is to provide a stove of this character comprising three essential parts—a grate, legs and fire pot, so constructed and arranged that they may be readily knocked down and set up, and the 15 fire pot made in sections having interlocking members, so that the sections may be separated and packed in a small package, together with the legs and grate.

Another object of the invention is to provide 20 a stove which is simple in construction and manner of setting up and knocking down, and having certain details of structure and combination of parts hereinafter more fully described.

25 In the accompanying drawings—

Figure 1 is a top plan view of my improved stove ready for use;

Fig. 2 is an enlarged vertical sectional view taken on the line 2—2 of Fig. 1;

30 Fig. 3 is a side elevation of Fig. 1, showing the fire pot and grate partly in section as well as the manner of securing the sections of the fire pot together;

Fig. 4 is a plan view of one of the fire 35 pot sections, showing the clamping ear in an extended position before being bent over to lock the sections against movement in respect to each other.

Referring now to the drawings, 1 represents the grate which is preferably made of 40 gray iron casting and of a circular form, although the material and shape could be varied without departing from my invention. The said grate is composed of a body 45 portion 2, having any number of openings 3 therein of any desired shape, to allow of the free passage of air therethrough, and equally spaced around the periphery thereof are the outwardly extending radially arranged lugs 4, which, in conjunction with the casing, as hereinafter more fully described, form the air spaces 4'. Between the lugs 4, the grate is provided with outwardly extending radially arranged lugs 5 which are of a considerable width and are provided in their lower faces with the ra-

dially arranged grooves 6, in which closely fit the lateral extensions 7 of the stove legs 8.

The lugs 5 are provided with counter-sunk openings 8 through which pass the bolts 9, which also pass through the openings 10 in the lateral extension of the legs and by means of the nuts 11 the legs are securely held in the sockets in the grate, as clearly shown in Fig. 2 of the drawings. The legs 8 are made preferably of band or bar iron and extend from the portion 7 in an outwardly oblique direction, whereby a larger base is provided and prevents any liability of the stove being top heavy and tilting over from a slight knock or pressure thereon.

The casing 12 forming the fire pot of the stove is made of three sections 13, 14 and 15, and each section made of the shape shown in Fig. 4 of the drawings. These sections are preferably made of blue annealed steel and have upper and lower curved edges 16 and 17, and downwardly converging end walls 18 and 19, which when bent in an arc of a circle and secured together form a tapering cylindrical fire pot having horizontal upper and lower edges, as clearly shown in Fig. 3 of the drawings. 85 Each fire pot section is provided with a series of key-hole slots 20 adjacent one edge and adjacent the opposite edge with headed lugs 21 adapted to coöperate with the key-hole slot of the abutting section, as shown 90 in Fig. 3 of the drawings.

The lower curved edge 17 of each section is provided with the cut-away portions 22 and 23, and the cut-away portion 22 of one section and the cut-away portion 23 of the other section form a notch 24 in the lower edge of the fire pot of a width to receive the lateral extension 7 of the leg, whereby the fire pot is held against oscillation in respect to the grate. The fire pot rests upon the 100 legs below the upper face of the grate and the lugs 4 and 5 carried by the grate will center the fire pot thereon. The fire pot can not possibly slip from around the grate in any direction, as clearly shown in the drawings.

The upper curved edge of each of the fire pot sections adjacent one edge is provided with an upwardly extending ear 25, which is adapted to be bent downwardly over the 110 upper edge of the overlapping adjoining section, whereby any vertical movement of

one section in respect to the other is prevented. By this arrangement, it will be seen that the key-hole slot connection between the three sections are prevented from being disconnected and the fire pot can be moved as a whole from its position in respect to the grate.

From the foregoing description, it will be seen that I have provided a stove of such character that the sections forming the fire pot may be readily separated and nested together for compact packing and the legs removed from the grate by the removal of the nuts, so that the entire stove may be packed in a small space and at the same time allow for the ready setting up of the stove.

Having thus described my invention, what I claim as new and desire to secure by Letters Patent, is:

20. 1. A stove of the character described, comprising a grate, legs supporting the grate and extending beyond the periphery thereof, and a fire pot loosely resting upon the legs and surrounding the grate and held against lateral movement by the grate.

25. 2. A stove of the character described, comprising a grate, legs supporting the same and a fire pot loosely supported by the legs and surrounding the grate and having notches for receiving the legs and said firepot held against lateral movement by the grate.

30. 3. A stove of the character described comprising a grate, legs removably secured to the lower face of the grate, and a fire pot loosely resting on the legs and surrounding the grate and held against horizontal movement by the grate.

35. 4. A stove of the character described comprising a grate, legs removably secured to the lower face of the grate, and a fire pot formed of a series of sections removably connected together and loosely resting on the legs surrounding the grate and held against horizontal movement by the grate.

40. 5. A stove of the character described comprising a grate, legs removably secured to the lower face of the grate, and a fire pot formed of a series of sections removably secured together and having notches to receive the legs and loosely resting thereon below the lower face of the grate and held against horizontal movement by the grate.

45. 6. A stove of the character described comprising a grate having outwardly extending lugs on its periphery provided with recesses in their lower faces, legs having lateral extensions secured in said recesses, a fire pot formed of a series of sections hav-

ing interlocking members securing them together, and resting on the lateral extensions of the legs and surrounding the grate and held against lateral movement by engagement with the lugs carried by the periphery of the grate.

65. 7. A stove of the character described comprising a grate, legs removably secured to the lower face of the grate, and a fire pot formed of a series of sections having key-hole slot connections securing them together against outward movement, and lugs carried by one edge of each section and overlapping the abutting sections to prevent lateral movement and said fire pot resting upon the legs below the lower face of the grate.

70. 8. A stove of the character described comprising a grate, legs removably secured to the lower face of the grate and extending outwardly beyond the periphery thereof in a horizontal direction and then downwardly in an oblique direction, a fire pot formed of sections having curved upper and lower edges and converging end walls adapted to be locked together by key-hole slot connections to form a tapering cylindrical fire pot having notches in its lower edge adapted to receive the lateral extension of the legs and support the same in a position surrounding the fire pot whereby the same is held against horizontal movement in respect to the grate.

75. 9. A stove of the character described comprising a grate having outwardly extending lugs on its periphery, said lugs having recesses in their lower faces, legs having lateral extensions bolted in said recesses, a fire pot formed of a series of sections, each section having a series of headed studs carried by one edge and key-hole slots carried by the opposite edge and adapted to interlock to form a tapering cylindrical fire pot, a lug carried by the upper edge of each section and adapted to be bent over the upper edge of the adjoining section to hold the same against longitudinal movement in respect to each other, and the lower edges of each section having notches to form a recess to receive the lateral extension of the legs, whereby the fire pot is supported on the lateral extension of the legs against oscillation and also against horizontal movement by engagement with the grate.

80. In testimony whereof I affix my signature in the presence of two witnesses.

JOSEPH E. LEONARD.
